(57) **CLAIM**

The ornamental design for a golf glove, as shown and described.

DESCRIPTION

FIG. 1 is a top view of a golf glove showing our new design; FIG. 2 is a perspective view of the golf glove of FIG. 1; and, FIG. 3 is a bottom view of the golf glove of FIG. 1.

The broken line showing of stitching in FIGS. 1-3 is for illustrative purposes only and forms no part of the claimed design.
